(57) **CLAIM**

The ornamental design for a dance footwear, as shown and described.

DESCRIPTION

FIG. 1 is a front perspective view of dance footwear illustrating my design;

FIG. 2 is a front elevation view thereof;

FIG. 3 is a top perspective view thereof;

FIG. 4 is a top plan view thereof;

FIG. 5 is a left side elevation view thereof;

FIG. 6 is a right side elevation view thereof; and,

FIG. 7 is a bottom plan view thereof.

The broken lines showing a human foot in FIG. 1 are for environmental purposes only and form no part of the claimed design.
